COMBINED FILLING STATION PUMP AND
VENDING MACHINE

Charles Walker, Knoxville, Tenn.

Application August 4, 1932. Serial No. 627,437

9 Claims. (Cl. 194—66)

My invention consists in new and useful improvements in vending machines and relates more particularly to that type of vending machine shown and described in my former Patent #1,867,429 dated July 12, 1932. As in the case of my former invention, it is my object to provide a machine which may be employed in vending liquids such for example as gasoline, in varying quantities according to the denomination of the 10 coin or coins inserted.

A further object of my invention resides in the means whereby the device may be used as an ordinary filling station pump.

With the above and other objects in view which 15 will appear as the description proceeds, my invention consists in the novel features herein set forth, illustrated in the accompanying drawings and more particularly pointed out in the appended claims.

Referring to the drawings in which numerals of like character designate similar parts throughout the several views,

Fig. 1 is a transverse vertical sectional view through the machine.

Fig. 2 is a sectional view taken on line 2—2 of Fig. 1.

Fig. 3 is a sectional view in the opposite direction taken on line 3—3 of Fig. 1.

Fig. 4 is a detail of the manual control and 20 gauge mechanism, and

Fig. 5 is a fragmentary detail of a modified form of my invention.

In the drawings, 1 represents the housing of the vending machine which is preferably rectangular in shape and provided in its top wall with a series of coin chutes 2, 3 and 4 adapted to receive five-cent, ten-cent and twenty-five-cent coins respectively.

Located substantially centrally of the housing 40 1 in suitable bearings 5 and 6 I provide a rotary shaft 7 which carries an upwardly projecting segment 8 arranged below and in alignment with the coin chutes just referred to. This segment may be integral with the shaft 7 or affixed thereto by any suitable means so as to be rotatable therewith.

9, 10 and 11 represent recesses in the upper face of the segment 8, extending transversely of the axis thereof and adapted to lie normally in direct 50 alignment with the coin chutes 2, 3 and 4 respectively whereby when a coin is inserted in either of said slots, it will fall into the corresponding recess in the segment 8. Intermediate the periphery of the segment 8 and the shaft 7 I provide a slot 12 which extends

through the segment longitudinally of the latter's axis and is adapted to accommodate a rock shaft 13 pivoted intermediate its ends as at 14 in the slot 12. This rock shaft 13 extends through the center of the recesses 9, 10 and 11 and is preferably provided at its pivotal point 14 with a pressure spring mechanism 14a adapted to retain the rock shaft in any one of its several positions, until returned to its normal position by the means hereinafter described. This spring mechanism 65 may be of any suitable form, that shown in Fig. 1 of the drawings comprising a coil spring encircling the pivot 14 and interposed between the vertical wall of the slot 12 and the adjacent portion of the rock shaft so as to constantly exert a 70 sufficient pressure on the latter to retain the same in any of its various operating positions.

In its normal horizontal position as shown in Fig. 1, the rock shaft 13 is adapted to support a coin resting in either of the recesses 9, 10 and 11 75 so that the upper edge of said coin will project slightly beyond the periphery of the segment. Due to the substantial difference in diameter between a ten-cent coin and those of the five-cent and twenty-five-cent coins, I preferably provide an upwardly projecting lug or support 15 which lies adjacent the ten-cent coin recess 10 so as to maintain a coin deposited in said recess sufficiently elevated that its upper edge projects above the periphery of the segment as shown in 80 Fig. 1. Toward one end of the rock shaft 13 the shaft 7 is provided with a vertically slotted guide 8a mounted on the shaft 7.

16 represents an abutment supported by a suitable bracket 17 extending from the top wall of the housing 1, said abutment being preferably inclined on its undersurface and disposed adjacent the upper periphery of the segment 8 immediately in advance of the path traveled by the coins in said segment in the counter-clockwise rotation 90 of the latter.

It will be noted that when the shaft 7 and segment 8 are rotated in counter-clockwise direction by the mechanism hereinafter described, the abutment 16 will depress the inserted coin and 95 rock the shaft 13 on its pivot 14, and in this connection it will be seen that due to the different elevations of the projecting edges of the coins in the recesses 9, 10 and 11 and the progressively decreasing distance between the 100 coins in the recesses 9, 10 and 11 respectively and the pivotal point 14 of the shaft 13, the different 105 coins, when coming in contact with the abutment 16 will vary the degree of rotation of the rock shaft 13 on its pivot 14. In other words, a twenty- 110

five-cent coin in the recess 11 will rock the shaft 13 through a greater arc than a coin in the recess 10, and likewise a coin in the recess 10 will rock the shaft 13 through a greater arc than a coin in 5 the recess 9.

Adjacent the long end 13a of the rock shaft 13, I provide a series of stationary stops 17, 18, 19 and 20 carried by a common supporting arm 21 depending from the underside of the top wall of 10 the casing, said stops being arranged in varying spaced relation substantially in the line of travel of the rock shaft 13 upon rotation of the main shaft 7 so as to cooperate with the end 13a of the rock shaft 13 in controlling the degree of rotation 15 of the main shaft 7. The stop 17 is arranged adjacent the normal horizontal position of the rock shaft 13 and thus prevents rotation of the shaft 7 in the absence of a coin in one of the recesses in the segment 8. The stop 18 is spaced 20 from the stop 17 a predetermined distance so as to obstruct the end 13a of the rock shaft after it has permitted the rotation of shaft 7 a distance sufficient to vend a quantity of liquid commensurate with a coin inserted in the five-cent recess 9. 25 In a similar manner the stops 19 and 20 cooperate with the rock shaft 13 upon the insertion of coins in the recesses 10 and 11 respectively.

Fixed on one end of the shaft 7 I provide a gear 22 which is adapted to mesh with a smaller gear 23 fixed on a horizontally extending rotary sleeve 24 supported at its outer end in the wall of the casing and at its inner end by a bearing 25, the outer end of said sleeve having affixed thereto a handle 26. A shaft 27 is located within 30 and co-axially of the sleeve 24 and extends through the small gear 23, its projecting end carrying a crank arm 28 which is operatively connected to the pump rod 29 of a suitable liquid dispensing or pumping device not shown. The gear 23 carries an internal pawl or the like 30 (Fig. 2) which is adapted to engage a ratchet tooth 31 fixed to the shaft 27 whereby upon the clockwise rotation of the sleeve 24 by the handle 26, the pawl 30 will engage the ratchet tooth 31 45 to cause the rotation of the shaft 27 and in turn the operation of the pumping device. On the other hand, the counter-clockwise rotation of the handle 26 will not be effective to cause the operation of the pumping mechanism, as the pawl 30 will ride over the ratchet tooth 31 without rotating the shaft 27.

On the opposite wall of the housing 1 adjacent the short end 13b of the rock shaft 13, I provide a series of pivoted members 32, 33 and 34 each of which is provided with a notch 32a, 33a and 34a respectively, said members being arranged in the path of movement of the end 13b of the rock shaft and constructed and weighted so that they automatically assume by gravity the positions indicated in Fig. 3 of the drawings, after the end of the rock shaft has passed by during the rotation of the main shaft 7. These members are so spaced with respect to one another and their notches so located that upon the reverse rotation of the shaft 7, the respective notch 32a, 33a or 34a will engage the end 13b of the rock shaft and through an eccentric movement will cause the rock shaft to be returned to its normal horizontal position.

70. 35 represents a coil spring having one end affixed to the main shaft 7 and its other end to the wall of the casing whereby upon the release of the handle 26, the main shaft and connected parts will be caused to return to their normal 75 positions.

In order to provide for the manual operation of this machine as a conventional filling station pump or liquid dispensing device, without the insertion of coins, I employ the mechanism 36 in Fig. 1. This mechanism comprises a relatively short screw threaded shaft 37 adapted to operatively engage complementary threads in an opening 38 in the side wall of the housing 1 immediately adjacent the short arm 13b of the rock shaft. The outer end of the threaded shaft 37 is provided with a suitable handle 39 and its inner end is beveled as at 40 so that when the handle 39 is turned in clockwise direction, the end 40 of the shaft 37 will be caused to engage the end 13b of the rock shaft, and due to the inclination of said end 40, the rock shaft will be turned on its pivot a distance corresponding to the extent of inward movement of the shaft 37.

In order to gauge the operation of the mechanism in this manner I provide a dial 41 which is calibrated for different coin values as shown in Fig. 4 and the shaft 37 is provided with a hand or indicator 42 adapted to cooperate with said dial. It will be noted that the calibrations on the dial are so arranged that when the shaft 100 37 has been screwed into the casing a sufficient distance to rock the shaft 13 to a point where its end 13a is in line for abutment with one of the stops 18, 19 or 20, the hand or indicator 42 on the shaft 37 will lie adjacent the corresponding calibration on the dial. The hand 42 is provided with an inwardly projecting lug 43 adapted to ride in a longitudinally extending slot 44 in the periphery of the threaded shaft 37 to cause said hand to turn with the shaft, and in 110 order to retain said hand in its proper position with respect to the shaft 37 I provide a coil spring or the like 45. This mechanism 36 is provided with a closure 46 which may be locked in place by any suitable means when the device 115 is to be employed as a coin actuated vending machine.

In Fig. 5 I have shown a modified form of my invention wherein the coin receiving recesses in the segment 8 are arranged longitudinally of the 120 axis of the segment and shaft 7. In this modified form it will be noted that the coin is presented sidewise to the abutment 16 instead of edgewise as in the former embodiment and in order to prevent undue friction and to facilitate 125 the operation of the mechanism, I provide a friction dog 47 pivoted to the segment 8 adjacent the coin recess and normally retained in the position shown in Fig. 5 by a spring 48. Upon the rotation of the segment 8 in the absence of a 130 coin in either of the recesses 9, 10 or 11, the friction dog 47 would engage the abutment 16 and rock on its pivot without effect, while on the other hand, if a coin is present in either of the recesses, the friction dog will engage the upper 135 end of the coin and force the same downwardly the proper distance to actuate the rock shaft 13.

In the operation of the machine for a coin controlled vending machine, a coin is inserted in the proper slot 2, 3 or 4 dropping by gravity to the corresponding recess 9, 10 or 11, and upon the clockwise rotation of the handle 26, the gear 23 will cause the counter-clockwise rotation of the gear 22 which in turn rotates the shaft 7 and segment 8 in counter-clockwise direction. 140 This rotation brings about the engagement of the coin with the abutment 16 and through the means heretofore described, rocks the shaft 13 on its pivot 14 out of alignment with the normal stop 17 and to a predetermined position in 145

alignment with the respective stop 18, 19 or 20, said rock shaft being retained in this position by the pressure spring 14a about its pivot 14. Simultaneously with the rotation of the main shaft 7 and connected parts, the pumping mechanism actuated by the pump rod 29 is thrown into operation, the extent of such operation being governed by the number of rotations permitted by the stop members 18, 19 or 20. In other words, if a five-cent piece be inserted in the slot 2, the stop member 18 would permit a predetermined number of rotations of the handle 26 to vend five-cents' worth of liquid whereupon the end 13a of the rock shaft would abut the stop 18 and prevent further rotation. After vending the desired quantity of liquid, the coin drops from the segment into any receptacle (not shown).

Upon releasing the handle 26 after vending five-cents' worth of liquid, the spring 35 will return the shaft 7 and connected parts to their normal positions, the member 32 adjacent the short arm 13b of the rock shaft causing said rock shaft to again assume its horizontal position as heretofore described.

It may be desirable to employ this mechanism as a coin controlled vending machine only after business hours and in the absence of an attendant, and during business hours to use the device as a conventional liquid dispensing machine. In this event, the closure 46 is removed from the manual control mechanism 36 and the operation of the machine is identical with that just described with the exception that instead of inserting a coin in the required slot, the handle 39 is employed to set the rock shaft for abutment with the proper stop. This is done by screwing the threaded shaft 37 inwardly until the indicator 42 comes adjacent a proper calibration on the dial 41 corresponding to the respective stop on the depending arm 21. The shaft 37 is then screwed outwardly and returned to normal position before the handle 26 is turned, the pressure spring 14a retaining the rock shaft 13 in operative position until the handle 26 is released. After completing the vending of the desired quantity of liquid, the spring 35 returns the shaft 7 and connected parts to their normal position, the member 32, 33 or 34, as the case may be, engaging the short arm 13b of the rock shaft and causing the same to assume its horizontal position in the manner just described in connection with the operation of the device by coin control. It will be noted that by returning the shaft 37 to normal position after setting the rock shaft, said shaft 37 is withdrawn from the path of movement of the short arm of the rock shaft in the return rotation of the rotary element 8 to permit the members 32, 33 or 34 to operate without interference in returning the rock shaft after vending.

From the foregoing it is believed that the construction and advantages of my invention may be readily understood by those skilled in the art without further description, it being borne in mind that numerous changes may be made in the details disclosed without departing from the spirit of the invention as set forth in the following claims. For example, while I have shown and described this mechanism as a liquid dispensing and vending machine, it may be employed for vending numerous articles of manufacture with equal advantage.

What I claim and desire to secure by Letters Patent is:—

1. A vending machine comprising a housing, a rotary shaft mounted in said housing, means operatively connecting said shaft with a vending device, means for rotating said shaft, a second shaft carrying a rotary element mounted in said housing and operatively connected to said first named shaft whereby the rotation of the latter will cause the rotation of the former, a lever fulcrumed on said element, means on said element adjacent a portion of said lever for receiving a coin with its lower edge resting on said lever and its upper edge projecting diametrically beyond said element, an abutment mounted in said housing and adapted to be engaged by the projecting edge of the coin in said element, upon the rotation of the latter to rock said lever on its fulcrum the desired degree, and a stop member arranged in the path of rotation of said lever when the latter is rocked on its pivot, whereby the rotation of said element and in turn the operation of said vending device are controlled by the insertion of a selected coin. 80
2. A vending machine comprising a housing, a rotary shaft mounted in said housing, means operatively connecting said shaft with a vending device, means for rotating said shaft, a second shaft carrying a rotary element mounted in said housing and operatively connected to said first named shaft whereby the rotation of the latter will cause the rotation of the former, a lever fulcrumed on said element, means on said element adjacent a portion of said lever for receiving a plurality of coins of different denominations with their lower edges resting on said lever and their upper edges projecting diametrically beyond said element, an abutment mounted in said housing and adapted to be engaged by the projecting edges of the respective coins in said element, upon the rotation of the latter to rock said lever on its fulcrum the desired degree, and a plurality of stop members arranged respectively in the paths of rotation of said lever when the latter is rocked various degrees on its pivot, whereby the rotation of said element and in turn the operation of said vending device are controlled by the insertion of a selected coin. 95
3. A vending machine comprising a housing, a rotary shaft mounted in said housing, means operatively connecting said shaft with a vending device, means for rotating said shaft, a second shaft carrying a rotary element mounted in said housing and operatively connected to said first named shaft whereby the rotation of the latter will cause the rotation of the former, a lever fulcrumed on said element, means for rocking said lever on its fulcrum varying degrees, and a plurality of stop members arranged respectively in the paths of rotation of said lever when the latter is rocked varying degrees on its pivot, whereby the rotation of said element and in turn the operation of said vending device are controlled by the relative position of said lever. 100
4. A vending machine comprising a housing, a rotary shaft mounted in said housing, means operatively connecting said shaft with a vending device, means for rotating said shaft, a second shaft carrying a rotary element mounted in said housing and operatively connected to said first named shaft whereby the rotation of the latter will cause the rotation of the former, a lever fulcrumed on said element, means for rocking said lever on its fulcrum varying degrees, a plurality of stop members arranged respectively in the paths of rotation of said lever when the latter is rocked varying degrees on its pivot, whereby 105

the rotation of said element and in turn the operation of said vending device are controlled by the relative position of said lever, and means for returning said lever to its normal position.

5 5. A vending machine comprising a housing, a rotary shaft mounted in said housing, means operatively connecting said shaft with a vending device, means for rotating said shaft, a rotary element mounted in said housing and operatively connected to said shaft whereby the rotation of the latter will cause the rotation of the former, a lever fulcrumed on said element, means for rocking said lever on its fulcrum varying degrees, a plurality of stop members arranged respectively 10 in the paths of rotation of said lever when the latter is rocked varying degrees on its pivot, whereby the rotation of said element and in turn the operation of said vending device are controlled by the relative position of said lever, means 15 for retaining said lever in its respective operative position, and means for returning the same to its normal position.

10 6. Apparatus as claimed in claim 5 wherein 20

the means for rocking said lever is coin controlled.

7. Apparatus as claimed in claim 5 wherein the means for rocking said lever is manually controlled.

8. Apparatus as claimed in claim 5 wherein said means for rocking said lever comprises a threaded shaft arranged longitudinally adjacent one end of said lever, the end of said shaft adjacent said lever being tapered and adapted to engage the end of said lever upon being rotated, and means for rotating said shaft.

9. Apparatus as claimed in claim 5 wherein said means for rocking said lever comprises a threaded shaft arranged longitudinally adjacent one end of said lever, the end of said shaft adjacent said lever being tapered and adapted to engage the end of said lever upon being rotated, means for rotating said shaft, and an indicator cooperating with said threaded shaft to indicate the degree through which said lever is rocked.
